COMBINED CAN OPENER AND KNIFE SHARPENER

Thomas W. Kellogg, Newport Beach, Calif., assignor to
Dazey Products Company, Kansas City, Mo., a corpora-
tion of Missouri

Filed Apr. 12, 1965, Ser. No. 84,740

Term of patent 14 years

(Cl. D37—1)

Fig.1.

Fig.2.

Fig.3.

Fig.4.

Fig.5.

FIG. 1 is a front elevational view of the combined can opener and knife sharpener, showing my new design;

FIG. 2 is an elevational view of one side thereof;

FIG. 3 is an elevational view of the side opposite to that shown in FIG. 2;

FIG. 4 is a rear elevational view thereof; and

FIG. 5 is a top plan view.

I claim:

The ornamental design for a combined can opener and knife sharpener, as shown and described.
